(57) **CLAIM**

The ornamental design for a ladder rest and restraining device, as shown and described.

DESCRIPTION

FIG. 1 is a perspective view of a ladder rest and restraining device showing my new design;

FIG. 2 is second perspective view thereof;

FIG. 3 is a third perspective view thereof;

FIG. 4 is a fourth perspective view thereof;

FIG. 5 is a top plan view thereof;

FIG. 6 is a bottom plan view thereof;

FIG. 7 is a rear elevation view thereof;

FIG. 8 is a right side elevation view thereof;

FIG. 9 is a left side elevation view thereof; and,

FIG. 10 is a front elevation view thereof.

The broken lines shown in the drawings are included for the purpose of illustrating environmental structure and form no part of the claimed design.
